UNITED STATES PATENT OFFICE.

CLOYD E. BURNS, OF NEW YORK, N. Y., ASSIGNOR TO REMINGTON TYPEWRITER COMPANY, OF ILION, NEW YORK, A CORPORATION OF NEW YORK.

TYPEWRITING MACHINE.

Application filed January 17, 1924. Serial No. 686,811.

My invention relates to collating mechanism for typewriting machines and its chief object is to provide improved means for collating or assembling work sheets in desired relationship preparatory to writing entries in duplicate at varying predetermined positions on the different sheets. Another object of my invention is to provide new and improved paper clamping devices; and still 16 another object is to provide new and improved paper guiding devices.

To the above and other ends which will hereinafter appear, my invention consists in the features of construction, combinations of 15 devices and arrangements of parts herein-after described and particularly pointed out in the claims.

In carrying out my invention in the present instance, I provide a bail comprising a 20 cross bar and which is hung or suspended from the platen carriage of the machine, the side arms of the bail being pivoted on the frame of tally roll mechanism which is mounted on the carriage. The cross bar of 25 the bail is disposed above the platen at its front side and provides a support for a pair of paper controlling or clamping contrivances which are individually settable at different points along the cross bar and lengthwise of the platen so as to take care of work 30 sheets of different widths. The paper clamping contrivances comprise each a plate-like portion on which is pivoted a clamping jaw, the clamping jaw carrying an inner side 35 edge guide for a narrow work sheet or bill and the plate-like portion having on it an outer side edge guide for a wider record or ledger sheet. The clamping contrivances are adapted to be opened and closed in 40 concert or simultaneously in all of their adjusted relationships by means comprising a rock shaft supported by the bail and provided with a finger piece, each contrivance having an individual train of connections 45 with the rock shaft, these trains being automatically adjustable along with the contrivances. The construction is such that the finger piece for controlling the clamps occupies a constant or single normal position 50 on its mounting, while the clamps may occupy a variety of set positions lengthwise of the platen. The entire mechanism may be thrown back out of the way fore-and-aft of

the machine by turning the bail on its pivots, thus affording access to the underlying tally 55 roll mechanism, with which my present invention is usually associated, as well as affording a ready means of dispensing with the mechanism when it is not to be used.

The present form of the invention may be 60 advantageously employed in connection with two work sheets such as a ledger or record sheet and a statement or bill, which may be used with the tally sheet, the three sheets 65 all being written on simultaneously by means of transfer sheets or carbons after the statement and ledger sheets have been collated or assembled in desired relationship.

In thus using the invention, the clamps are first opened together and the feed rollers 70 that co-operate with the platen are thrown off by the usual release or in some cases automatically. The ledger and statement sheets with an interleaved carbon are inserted together from the back and moved around 75 under the platen and up at the front past the printing line and over the cross bar of the bail and the plate-like parts of the clamps. The clamps having been properly set or spaced apart for the record sheet, the latter 80 will be guided between the fixed side guides on said clamps and in close proximity thereto, either or both of the guides serving as a side edge gage or gages. The usual line 85 finder of the machine is employed to gage the record sheet vertically. The record sheet having thus been properly positioned, the clamps are simultaneously thrown on to clamp its side edges above the printing line, thus leaving both hands of the operator free 90 properly to adjust the bill sheet which may be in the present case aligned lengthwise of the platen against the left-hand side edge guide carried by the clamping jaw, the bill sheet being so narrow as to pass inside the 95 clamping jaws. The vertical alignment of the bill sheet is effected by the regular line finder. The invention will be described in detail and explained more at length in connection with the accompanying drawings 100 105 wherein

Figure 1 is a perspective view of the preferred form of my invention.

Figure 2 is a fragmentary end view of my invention applied to the carriage of a Remington typewriting machine.

Figure 3 is an end view partly in section showing the left-hand paper clamping contrivance as viewed from the right-hand side, the clamp being closed.

5 Figure 4 is a view corresponding to Fig. 3 but showing the clamp open.

Figure 5 is a sectional view taken on the section line 1—1 in Figure 3 and looking in the direction of the arrows at said line.

10 Figure 6 is a fragmentary detail view.

As appears from Fig. 2, the top plate 1 or open framing of the Remington typewriting machine, to which the present form of my invention is shown as applied, is provided with

15 posts or lugs 2 and 3 to which are secured fixed grooved guide rails 4 and 5, said rails co-operating through anti-friction rollers 6

with the front and rear grooved bars 7 and 8 of a rectangular carriage truck that further comprises end bars 9. Supported on the carriage truck is a platen frame or carrier comprising end bars 10 on which is journaled a cylindrical or roller platen 11. Co-operative with the platen, are the usual paper

25 feeding devices comprising main and secondary rollers, conventionally illustrated and numbered respectively 12 and 13, these feed rollers normally co-operating with the platen to advance the paper thereover when the platen is turned.

Said feed rollers are adapted to be thrown off or released by releasing devices comprising a rock shaft 14 which extends from side to side of the platen frame and is supported in the end bars 10, said shaft being

35 provided near its left-hand end with a release key comprising an upstanding crank arm 15 terminating in a finger piece or key 16. The throw-off or released position of the feed rollers 12 and 13 is illustrated by dotted lines in Fig. 2.

The platen may be turned for feeding the paper by the usual line spacing devices or finger wheels, not shown herein, the line spacing handle being effective not only to turn the platen through

40 line space distances, but also when sufficiently pressed to restore the platen and platen carriage comprising the platen frame and the truck from left to right to position the platen for beginning a new line of writing, the writing being effected with the usual

45 ribbon and type bar mechanisms.

Tally strip mechanism shown herein corresponds with that disclosed in the pending application of F. A. Hart, Sr. No. 570,220,

55 filed June 22, 1922, and comprises two angular brackets, each composed of a long horizontally disposed arm 17 and an upright arm 18 (Figs. 1 and 2). The arms 18 in the

60 present case are somewhat longer than those disclosed in the aforesaid application of

Hart. These angular brackets are connected by tie rods 19 and 20, making a supporting frame which is mounted on the carriage, the forward ends of the arms 17 being pivotally

65 connected at 21 at the ends of the usual scale

and margin stop bar 22 which is secured to the front truck bar 7. The tally frame proper comprises side arms 23 which are slidably and adjustably supported on the tie rods 19 and 20 of the supporting frame aforesaid, said tally frame carrying the carbon roll 24, the delivery roll 25 for the paper and the paper receiving roll 26. Inside the arms 23 are arranged friction rolls 27 which are co-axial with the lower tie rod 19 and bear on the top of the platen 11 being adapted to transmit rotary motion from the platen to the tally mechanism as explained in the aforesaid application of Hart.

My novel collating mechanism is pivotally supported on the tally supporting frame and through it on the platen carriage, said collating mechanism being readily detachable as a whole from its support. Said collating mechanism comprises a bail which is composed of two side arms 28, provided at their lower ends with inwardly projecting tabs or ears 29 to which are clamped the end portions of a cross bar 30 by means of screws 31,

the bail parts being rigidly connected by the screws so as to provide substantially a unitary frame. The bail is pivoted on the tally support, the upper end portions of the arms 28 being formed with bearing openings

which fit over pivot screws 32 that are threaded into the upper ends of the arms 18 and project laterally inward therefrom. At their lower end portions, the side arms 28

are provided with outwardly projecting stop lugs 33 which normally bear against the front edges of the arms 18, as shown in Fig. 2, and thus determine the normal position of the bail 28, 30 on its support. This locates the bar 30 in a position above the platen and at its forward side so that work sheets being

fed upward from the forward or delivery side of the platen are advanced at the front side of said bar. At their upper ends, the arms 28 are formed with outwardly projecting stop lugs 34 which are adapted to limit

50 the backward movement of the bail and the parts supported thereon when said bail is swung upward and rearward on its pivots 32, this extreme backward position being represented by dotted lines in Fig. 2. The

55 bail 28, 30 may be readily detached from its support by pressing inward against the arms 28 near their upper ends, the arms having sufficient spring to enable them to clear or disengage from the pivot screws 32 so that

60 the bail and the parts supported on it may be readily slipped out of the machine. Means are provided for preventing side vibration of the bail when it is in normal position on its support, said means comprising a

65 plate 35 (Fig. 1) which is arranged behind the left-hand ear 29 and is secured to the bail by the left-hand pair of screws 31, the plate 35 being confined between the heads of

70 said screws and the back of said ear. The

75 plate 35 is secured to the side arms 28 by the right-hand pair of screws 31, the plate 35 being confined between the heads of

80 said screws and the back of said ear. The

85 plate 35 is secured to the side arms 28 by the right-hand pair of screws 31, the plate 35 being confined between the heads of

90 said screws and the back of said ear. The

95 plate 35 is secured to the side arms 28 by the right-hand pair of screws 31, the plate 35 being confined between the heads of

100 said screws and the back of said ear. The

105 plate 35 is secured to the side arms 28 by the right-hand pair of screws 31, the plate 35 being confined between the heads of

110 said screws and the back of said ear. The

115 plate 35 is secured to the side arms 28 by the right-hand pair of screws 31, the plate 35 being confined between the heads of

120 said screws and the back of said ear. The

125 plate 35 is secured to the side arms 28 by the right-hand pair of screws 31, the plate 35 being confined between the heads of

130 said screws and the back of said ear. The

plate 35 extends downward and is off-set upward, and its lower end is formed with a slot indicated at 36, said slot having a flaring mouth and being adapted to pass down over the arm 17 of the left-hand tally bracket. The width of the slot near its upper end is such that the locking plate 35 snugly engages with the arm 17 providing an interlock between the bail 28, 30 and the tally 10 supporting frame.

The bail 28, 30 serves as a support for a plurality of individual paper controlling or collating contrivances which are adjustably mounted independently of each other on the cross bar 30. Each contrivance, designated as a whole by the numeral 37, comprises a plate-like or tabular support for paper, a paper clamp and two paper guides or gages which are alternatively disposed for use.

Each plate-like part 38 terminates at its upper end in a rearwardly curved or hood-like portion 39, the lower end of the plate being bent rearward as indicated at 40. The outer end of each plate is angularly bent forward at right angles to the body portion, providing an ear 41. Projecting from the rear face of each plate are the cone-like heads 42 of rivets 43. There are two of these coned rivets 42, 43 spaced apart on each plate so that the heads 42 may engage with the upper edge portion of the supporting bar 30, this edge of the bar being beveled to co-operate with the coned heads. The lower edge of the bar 30 is oppositely beveled and is engaged by a wedge, clamp or plate 44 which is secured against the back of the plate 38 by a screw 45. Lugs 46 struck rearward from the body of the plate 38 provide seats for the plate 44 at its lower side and prevent it from turning or being displaced. The upper or beveled edge of the plate 44 fits the bevel at the bottom of the bar 30, and when the screw 45 is tightened it wedges the bar up under the coned rivet heads 42, thus securing or clamping the plate 38 and through it the whole contrivance 37 in fixed or set position on the bar 30. By loosening the screw 45 the contrivance is freed so that it may be slid along the bar 30 and adjusted in any desired position after which it may be set or fixed by tightening the screw 45. The plate 38 not only receives and supports the paper when it is fed upward from the platen but also constitutes a support for the other parts of the contrivance 37. Secured to the outer face of each ear 41 by rivets 47 is a bracket comprising an upright portion 48 provided with parallel outwardly extending ear portions 49. These ear portions are perforated to provide bearing openings for an upright rod or rock shaft 50 which serves as a support for a clamping member or jaw. Said member comprises a curved crank or arm 51 provided with a hub portion 52 fitting over the associate rock shaft 50 and pinned thereto between its ends at 53. A crank arm curves forward and inward around both the bracket part 48 and the ear 41 and in front of the associate plate 38 terminates in a downwardly bent ear 54. This ear receives a screw 55 which secures to the crank 51 the clamping jaw proper, said jaw being in the form of a short arm 56 having rounded ends and which extends downward behind the ear 54 against which the arm is 75 clamped and held fast by the screw 55. The arm 56 is adapted to be maintained normally engaged with the face of the plate 38. Secured to the front face of the lower end of the arm or clamping jaw 56 by a screw 57 is 80 an ear or lug 58 which projects outward from and at right-angles to a plate-like side guide 59 that is disposed at right-angles to the face of the plate 38 and is adapted to contact with said plate along its rear edge, 85 said side guide covering both the associate ear 58 and the clamping arm 56. It will be understood that the side guides 59 of the two contrivances 37 project inward towards each other, the two constituting inner side 90 guides or gages for the narrow work sheet or bill.

Outer side guides or gages for a wider sheet, such as a record or journal sheet, are constituted by flat pieces or plates 60, one 95 for each contrivance 37. Each plate 60 is secured to the inner face of the associate ear 41 by screws 61 and projects outward at right-angles from the associate plate 38 with which it is held in unvaried rigid relationship by the screws 61. As appears from Figs. 1 and 2, the lower end portions of the outer guides or gage plates 60 extend downward towards the platen below the plates or supports 38 and terminate somewhat above 100 the printing line. The plates or gages 60 are so related to the platen that as the wider work sheets advance upward past the printing line they are almost immediately brought within the control of said side guides 60. It 105 will be understood that the relationship between the side guides 60 may be varied by readjusting the contrivances 37 bringing the side guides closer together or spacing them further apart according as the contrivances 110 are moved inward or outward. This likewise applies to the inner guides 59 which are also supported on the contrivances 37. During such readjustment of the contrivances, the relationship of the inner guide 59 and its 115 companion outer guide 60 on each contrivance is not altered. However, the mounting of the guide 59 affords means for varying the relationship between it and its associate or companion guide 60 without disturbing the set position of the contrivance 37 on which they are supported. Thus by loosening the two screws 55 and 57, the arm 56 may be swung inward on the screw 55 as a 120 pivot to the position for example illustrated 125 130 135

by dotted lines in Fig. 5, and concurrently the guide 59 may be turned on the screw 57 as a pivot so as to maintain said guide upright or parallel with the position from which it started, after which the two screws may be tightened to set the guide 59 in the position illustrated by dotted lines in Fig. 5. By this means, it will be seen that the guide 59 has been reset so as to move it inward to a greater distance from its associate guide 60, thus altering the set relationship between the two guides independently of movement of the contrivance 37. Assuming that the guides 59 on both contrivances 37 have been similarly re-set, it will be seen that the two guides 59 had been adjusted to receive a narrower sheet. However, this readjustment is particularly convenient when a bill sheet and a record sheet having different relative widths from those previously in use are to be employed.

The inner side guides 59 are held against vertical displacement by means co-operating with their pivotal supports or shafts 50 and comprising collars 62 pinned to the shafts below the associate upper ears 49. These collars prevent upward displacement of the shafts in their bearings, while downward displacement of said shafts is prevented by collars or hubs 63 which are pinned or otherwise suitably secured to the end portions of said shafts projecting above the upper bearing ears 49. The collars 62 and 63 do not grip the interposed ears 49, and hence the shafts 50 are free to turn in their bearings. Integral with the hubs 63 are short crank arms 64 which are comprised in the operative connections for the guides 59. Said guides as well as the paper clamps proper 56 are spring pressed, being constantly affected by spring means which tend to keep them normally pressed into engagement with the plates 38 as illustrated in Figs. 1, 2, 3 and 5. Said spring means for each clamp 53 and guide 59 comprise a wire spring 65, which as illustrated in Fig. 5, is coiled around the associate shaft or rod 50 below the hub 52, the upper end of said spring being secured to said hub. The spring is housed within the bore 66 of a sleeve or thimble 67 which is rotatably supported on the shaft 50. The thimble 67 has a solid lower end 68 which is, however, perforated to afford passage-way for the shaft 50 which passes through it, said end 68 seating on the associate lower bearing ear 49. The lower end of the spring 65 is secured in the solid end 68. The upper end of the thimble or housing 67 is left open so that the bore 66 of the thimble may fit loosely and rotatively on the lower end of the hub 52, the parts being so related as to afford room for a slight upward movement of the thimble lengthwise of the shaft 50. For convenient manipulation of the thimble 67, its outer surface may be roughened or knurled at its lower end portion. The thimble on its outer face is formed with a plurality of vertical kerfs or slotways 69, there being four of such kerfs in the present instance equidistant from each other. Adapted to engage with the kerfs is a pin or lug 69^a projecting outward from the bracket portion 48, the pin acting in co-operation with the slots to hold the thimble from turning under the impulse communicated from the spring 65. By sliding either thimble upward on the shaft 50 and hub 52 to the position illustrated in Fig. 6, it may be disengaged from the pin 69^a so that it may be freely turned to increase or lessen the power or tension of its spring 65. After the spring has been adjusted to the desired tension, the thimble may be lowered, causing one of the kerfs 69 to re-engage with the pin 69^a, thus fixing the thimble and anchoring the lower end of the spring 65. The tension of the spring is communicated through the hub 52 to the crank arm 51 and thence to the associate clamping jaw 56 and side guide 59, the spring impulse maintaining a clamping or frictional engagement between the clamping jaw and the co-operating surface of the associate plate 38. Said spring also maintains the side guide 59 in normal relationship with the plate.

In order to overcome their springs and throw the clamping jaws and side guides away from the plates 38, or in other words, to open the clamps and expose the outer side guides 60, hand operated means are provided comprising a rock shaft 70 which is disposed above the supporting bar 30 and parallel therewith, the end portions of said rock shaft or rod 70 bearing in the side arms 28 of the supporting bail, said side arms being perforated for the purpose. In order to prevent endwise displacement of the rock shaft 70, its bearing portions are reduced somewhat in diameter from the body portion of the shaft forming shoulders inside the bearings 28. The left-hand reduced portion 71 of the shaft 70 is extended outward beyond the bearing and receives a finger piece in the form of a twirler or knob 72, as illustrated in Fig. 1. The finger piece or twirler 72 is suitably fixed to the outer end of the reduced portion 71 of the shaft. Slidably mounted on the shaft 70 are crank arms 73 having hubs 74 which fit over the shaft and are provided with inward projections or lugs 75 which engage slidably in a longitudinal groove or cut-out, indicated at 76, formed in the shaft. The construction is such that the crank arms may be slid freely lengthwise of the shaft 70 but the splined connection 75, 76 prevents independent rotation of the crank arms 73 and hubs 74 on the shaft 70 and forces them to turn when the shaft is rocked. The crank arms 73 are connected with the crank arms

64 on the shafts 50 by wire links 77 which transmit motion from the shaft 70 to the shafts 50. The curved upper ends or hoods 39 of the plates 38 extend over the top of the shaft 70 but without normally contacting therewith. However, any tendency of the shaft 70 to flex or blow upward during operations will be overcome by said hoods 39 which will then serve as braces or bearings 10 for the shaft.

Means are provided for connecting the trains comprising the crank arms 73 and links 77 with the contrivances 37 so that when said contrivances are adjusted along 15 their common support 30, said connecting trains may be automatically adjusted at the same time and yet be always adapted to transmit movement from the horizontal shaft 70 to the two vertical shafts 50 at right angles thereto. In the present instance, the aforesaid means comprises clips 78 which at their inner ends are secured by rivets 79 to the tops of the hood-like portions 39 on the plates 38. Said clips 78 extend outward 20 over the tops of the hubs 74 and crank arms 73, being bent upward to provide off-sets 78^a so as not frictionally to engage with said crank arms and hubs. The outer ends of said clips are bent downward as indicated 25 at 80 outside the crank arms 73. The construction is such that the crank arms 73 and their hubs are loosely confined between the clip ends 80 and the hood-like portions 39 of the plates 38, so that while the rotary movements of the crank arms with the rock shaft 70 are not interfered with, said crank arms will nevertheless be compelled to move slid- 30 ably on the rock shaft when the associate contrivances are moved along their support 30. The clip ends 80 will force the crank 73 to move inward; while the hoods 39 will engage the cranks when the contrivances 37 are pressed apart and will force the cranks and the connected ends of the links 77 to slide and move outward away from each other.

It will be understood that the position of the finger piece 72 will remain constant or unchanged for all of the adjusted positions of the contrivances 37 and their trains of 35 connections; and that by turning the finger piece in the direction of the arrow in Fig. 3, the springs 65 will be overcome and the clamps opened, while a reverse turning permits the clamps to close. Thus the turning 40 of the finger piece in the direction indicated likewise rotates the rock shaft 70 and swings the crank arms 73 from the front or Fig. 3 position backward to the Fig. 4 position. This movement of the crank arms pulls the 45 links 77 rearward and turns the crank arms 64 from the front outward, such movement being transmitted through the shafts 50 to the crank arms 51 and the clamps and guides carried by said crank arms, the clamps being 50 thus simultaneously opened or swung

outward from the Fig. 3 to the Fig. 4 position. The latter part of the movement is assisted by the clamp springs. Comparing the relations of the parts in Figs. 3 and 4, it will be observed that the effect of the 70 springs 65 as transmitted through the links 77 is in one case to hold the clamps closed against the co-operating parts 38 and in the other case to hold the clamps open, the limit of movement being determined by the ex- 75 treme backward limit to which the crank arms 73 can be pushed by the links 77 under the impulse of the springs, as in Fig. 4. In other words, the clamp springs 65 are double acting, serving to hold the clamps 80 closed and also to hold them open. In order simultaneously to close the clamps from their open or in-operative position, Fig. 4, it is only necessary to turn the finger piece or key 72 oppositely from the direction of the 85 arrow in said figure.

It will be understood that the embodiment of my invention as above described is capable of a variety of uses and that parts of the invention may be used without other parts. The present construction however was particularly designed and is well adapted for collating a narrow statement or bill sheet and a wider record or ledger sheet. 90 As is well understood, the depth of the previous written matter on the two sheets may vary according to circumstances, so that successive pairs of sheets require varying assembling or collating. In Figure 1 of the drawing, the wide or record sheet is designated as *a*, the bill sheet or statement is designated as *b* and the transfer or carbon sheet interposed between the sheets *a* and *b* is designated as *c*. This carbon sheet *c* is adapted to offset impressions on the underlying record sheet *a* simultaneously with the printing of the bill sheet *b*, which is effected through the usual ink ribbon. Let it be assumed that the clamping contrivances 37 have been adjusted on their support so that the record sheet *a* may pass freely between the outer side guides 60; and also that the inner side guides 59 and more particularly the left-hand one, has been adjusted relatively to its associate guide 60, so as to leave the proper left-hand margin exposed on the underlying record sheet *a*. In operation, the clamps are opened and the main and secondary feed rollers 12 and 13 are thrown off or released, 95 as shown by dotted lines in Fig. 2. The operator then introduces the sheets *a*, *b* and *c* together from the rear over the usual paper table, not shown, passing the sheets under the platen and up at its forward side. It may be stated that the carbon sheet is slightly 100 longer than the record sheet *a*, but in width, approximately of the width of the bill sheet *b*. Preferably the carbon sheet is folded along its upper edge suitably to engage the 105 upper edge of the record sheet, that is in- 110 115 120 125 130

roduced under the fold, so that the two sheets may be readily handled together.

As the sheets *a*, *b* and *c* are advanced at the front side of the platen under the usual line gage 81, the record sheet *a* will be guided into substantially the proper position lengthwise of the platen by the outer side guides 60 between which the side edges of sheet *a* will just pass. Vertically the record sheet will be positioned by the aid of the line gage 78, and said sheet will be advanced or pushed up until the next line to be printed on it registers with the line gage. To facilitate adjustment in respect to the line gage, a cross mark (Fig. 1) or other suitable indicia may be written in the right-hand margins on completion of the last prior entry on the record and bill sheets. After such adjustment, the finger piece 72 is actuated to throw the clamps together on or into engagement with the side edge portions of the sheet *a* above the printing line, said sheet being held or clamped by the co-operation of the movable clamping elements 56 with the plate 38. Both hands of the operator are thus left free for the collating or assembling of the bill sheet *b* in proper superposed relationship with the record sheet *a*. To this end the bill sheet is adjusted lengthwise of the platen by the aid of the left-hand side guide 59. As shown in the drawing, the right-hand side guide 59 is spaced rightward so that it does not co-operate with the right-hand edge of the bill sheet. It will be plain, however, that if desired, this right-hand guide may also be adjusted to co-operate with the bill sheet. The bill sheet is next adjusted in the proper position vertically by the aid of the line gage 81, after which the feed rollers 12 and 13 are thrown on as by actuating the finger piece or key 16, the feed rollers holding the work sheets in collated relationship so that the clamps may be simultaneously opened by actuating the finger piece 72. The writing of the collated sheets may then be proceeded with in the usual way. After the writing on the sheets is completed, they are withdrawn and the above outlined operations repeated with succeeding pairs of sheets that are to be collated and written upon. As has been previously stated, the typewritten matter may further be duplicated with the aid of the tally roll mechanism, the tally sheet serving as a register or proof sheet.

It will be observed that by my present invention there is provided collating mechanism comprising a plurality of paper clamping contrivances, each of which includes a single clamping jaw and a separate or individual support therefor, the supports being independent of each other; that means are provided for both simultaneously opening and also simultaneously closing the clamping jaws in all of the positions in which said

contrivances may be set, said means comprising a finger piece having an unvarying or constant normal position for all of the adjusted positions of the contrivances; that the pair of contrivances or devices provided in the present instance are adjustable along a supporting bar forming part of a bail which is mounted on the platen carriage of the machine through a tally roll frame carried by the carriage and on which said bail is pivoted; that the two clamping devices or contrivances carry two pairs of paper guides or gages, an inner and an outer pair, the inner pair being adapted for use with work sheets which are not to be controlled by the clamps; that one pair of the paper guides is movable into and out of position by the same finger piece that controls the clamps proper; and that said last mentioned paper guides together with the clamps proper are operatively connected with said finger piece by trains of connections which are adjustable automatically when the paper clamping contrivances are adjusted; that the paper guiding or gaging means comprise relatively adjustable side guides, which guide the same side edges of the work sheets that are superposed or to be collated; that two guides are provided at the same side of the machine, one movable out of the way of the other, the latter or outer being for the wider sheet, the movable or inner guide being for the narrower sheet; that the movable guide is raised or swung out of the way of the other and substantially over the other or outer guide; that the two guides have a common adjustable support which may be adjusted to vary the positions of the guides relatively to the platen; and that means are provided for adjusting the said two guides relatively to each other so as to vary their distance apart.

Various changes may be made without departing from my invention.

What I claim as new and desire to secure by Letters Patent is:—

1. In a typewriting machine, the combination of a platen, a bar disposed parallel with the platen, a plurality of clamps adjustable on said bar lengthwise of the platen, and means both for opening and for closing said clamps simultaneously, said clamps operating independently of the platen to positively clamp the paper against displacement or adjustment over the face of the platen.

2. In a typewriting machine, the combination of a platen, a supporting bar, a pair of clamping devices independently adjustable along said bar and adjustable to clamp the paper independently of turning movements of said platen, and means for opening and closing said clamps together.

3. In a typewriting machine, the combination of a platen, a supporting bar, a pair of clamping devices independently adjustable along said bar and adjustable to clamp the

paper independently of turning movements of said platen, and means effective to open and close said paper clamps together; said means comprising a finger piece having a single normal position.

5. In a typewriting machine, the combination of a platen, a supporting bar, a plurality of clamps adjustable along said bar lengthwise of the platen, each clamp comprising two cooperative clamping parts both of which are adjustable along said bar with the clamp in which they are comprised, and means for simultaneously opening said clamps and closing said clamps, said means comprising a finger piece having a single normal position.
10. In a typewriting machine, the combination of a platen, a bar extending longitudinally thereof, a plurality of paper clamps adjustable along said bar independently of each other, a rock shaft, a finger piece fixed to said rock shaft, and trains of connections between said rock shaft and said paper clamps, said finger piece operating through said trains being effective both to open and close said clamps simultaneously.
15. In a typewriting machine, the combination of a platen, a bar extending longitudinally thereof, a plurality of paper clamps adjustable along said bar, a rock shaft, a finger piece fixed to said rock shaft and having an unvarying normal position on its support, and trains of connections between said rock shaft and said paper clamps, said trains being adjustable lengthwise of said rock shaft simultaneously with the adjustment of said clamps, said finger piece operating through said trains being effective both to open and close said clamps simultaneously.

20. In a typewriting machine, the combination of a platen, a plurality of paper clamps, each of said clamps comprising a plate-like part and a pivotal part supported by said plate-like part; and means for simultaneously turning said pivotal parts on their pivots, said means comprising a rock shaft provided with a finger piece and separate trains of connections between each of said pivotal parts and said rock shaft.
25. In a typewriting machine, the combination of a platen, a plurality of paper clamps, each comprising a movable clamping part; and means for simultaneously moving said movable parts relatively to the remaining parts of the clamps both to open and to close the clamps simultaneously, said means comprising a hand controlled rock shaft and separate trains of connections between each of said movable parts and said rock shaft.

30. In a typewriting machine, the combination of a platen; a plurality of paper clamps, each comprising a movable clamping part; means for simultaneously moving said movable parts relatively to the remaining parts of the clamps both to open and close the
35. In a typewriting machine, the combination of a platen, a supporting bar, a plurality of paper clamps adjustable along said bar lengthwise of the platen, each clamp comprising two cooperative clamping parts both of which are adjustable along said bar with the clamp in which they are comprised, and means for simultaneously opening said clamps and closing said clamps, said means comprising a finger piece having a single normal position.

clamps simultaneously, said means comprising a hand controlled rock shaft and separate connections between each of said movable parts and said rock shaft, each of said connections comprising a crank arm adjustable on said rock shaft, and a link connecting said crank arm with said movable part.

40. In a typewriting machine, the combination of a platen; a bar extending longitudinally thereof; a paper clamping contrivance adjustable along said bar and comprising a movable clamping part; a key controlled rock shaft; a train of connections between said rock shaft and said contrivance for transmitting movement from said shaft to said movable clamping part; and means for automatically adjusting said train when said contrivance is adjusted, said rock shaft remaining quiescent during the adjustment of said train.

45. In a typewriting machine, the combination of a platen, a supporting bar, a paper clamping contrivance mounted on said bar, said contrivance comprising a plate-like part slideable on said bar, a clamping part pivoted to said plate-like part, a hand controlled rock shaft, a crank-arm slideable along said rock shaft, a link connecting said crank arm with said pivoted part, and a connection extending from said plate-like part to said crank arm for adjusting said crank arm on its rock shaft when said contrivance is adjusted on said supporting bar.

50. In a typewriting machine, the combination of a platen, paper controlling contrivances adjustable lengthwise of said platen, vertical shafts supporting said contrivances, a horizontal shaft, and connections adjustable with said contrivances for transmitting movement from said horizontal to said vertical shafts.

55. In a typewriting machine, the combination of a platen, a paper clamping contrivance adjustable lengthwise of said platen and adapted to clamp a work sheet near one end of said platen, and a plurality of side guides adjustable with said clamping contrivance.

60. In a typewriting machine, the combination of a platen, a paper clamping contrivance adjustable lengthwise of said platen, a paper side guide on said contrivance for a sheet to be clamped by said contrivance and a second side guide for a work sheet that is clear of said clamp.

65. In a typewriting machine, the combination of a platen, a paper clamping contrivance adjustable lengthwise of said platen, and a plurality of side guides on said contrivance, one of said guides being movable out of the way to render another of said guides accessible.

70. In a typewriting machine, the combination of a platen, a plurality of individual paper clamps, each comprising a plate-like

- part, a movable part pivotally supported by said plate-like part, spring means for each clamp tending to press the two parts together, and turning means for simultaneously turning the pivoted parts of said clamps on their pivots in opposition to said spring means and also for controlling the movements of the pivotal parts in the opposite direction.
10. 17. A paper clamp for a typewriting machine comprising a plate-like part, a movable part pivotally supported by said plate-like part, spring means tending to press the two parts together, and devices for varying the tension of said spring means at will; in combination with hand operated means for simultaneously turning said pivotally supported parts of a plurality of such clamps in opposition to said spring means.
15. 18. In a typewriting machine, the combination of a platen, a plurality of paper clamps, each comprising a plate-like part, a movable part pivotally supported by said plate-like part, spring means for each clamp tending to press the two parts together, and turning means for simultaneously turning the pivoted parts of said clamps on their pivots in opposition to said spring means, said turning means comprising a rock shaft provided with a finger piece and separate connections between each of said pivotal parts and said rock shaft.
20. 19. In a typewriting machine, the combination of a platen, a plurality of paper clamps adjustable lengthwise of the platen and each comprising a slidable plate and a clamping jaw pivoted thereon, spring devices one for each clamping jaw, means for separately varying the tension of said spring devices, and means controlled by a single finger piece for simultaneously moving said clamping jaws on said clamps in opposition to said spring devices.
25. 20. In a typewriting machine, the combination of a platen, a pivoted paper controlling device, a shaft on which said device is mounted, a spring coiled around said shaft and having one end connected thereto, and an adjustable anchorage for the opposite end of said spring, said anchorage comprising a thimble rotatably supported on said shaft, and means normally preventing rotation of said thimble.
30. 21. In a typewriting machine, the combination of a platen, a pivoted paper controlling device, a shaft on which said device is mounted, a spring coiled around said shaft and having one end connected thereto, and an adjustable anchorage for the opposite end of said spring, said anchorage comprising a thimble rotatably and slidably supported on said shaft and having notches on its outer face, and a relatively stationary projection co-operative with said notches to prevent rotation of said thimble, said thimble being slidable endwise on said shaft to free it or for adjustment in a rotary direction to vary the power of said spring.
35. 22. In a typewriting machine, the combination of a platen, a plurality of slidable paper clamps, each comprising a pivoted clamping jaw, means for simultaneously controlling said clamping jaws both during opening and closing movements, and double acting springs which are adapted both to maintain said clamping jaws in operative position and also to hold said clamping jaws out of operative position.
40. 23. In a typewriting machine, the combination of a platen, a contrivance adjustable relatively to the platen and comprising a plurality of side guides co-operative with the plurality of superposed work sheets at their same side edges, and means for affording relative adjustment between said side guides and holding them positively in set operative relationships without affecting the position of said contrivance as a whole relatively to the platen, such adjustment affording variation in the widthwise relationship of the two work sheets.
45. 24. In a typewriting machine, the combination of a platen, and a paper clamping contrivance adjustable as a whole lengthwise of the platen, a pair of side guides on said contrivance for co-operation with superposed work sheets at their same side edges, and means for affording relative adjustment between said side guides and holding them positively in set operative relationships.
50. 25. In a typewriting machine, the combination of a platen, a paper clamping contrivance adjustable as a whole lengthwise of said platen and comprising a clamping jaw, a side guide on said clamping jaw, and a second side guide on said contrivance mounted independently of said clamping jaw.
55. 26. In a typewriting machine, the combination of a platen, a paper clamping contrivance adjustable lengthwise of said platen and comprising a clamping jaw, a side guide on said clamping jaw, and a second side guide on said contrivance mounted independently of said clamping jaw, one of said side guides being movable to afford access to the other.
60. 27. In a typewriting machine, the combination of a platen, a platen frame, a bar thereon, a contrivance adjustable along said bar, a pair of paper side guides mounted on said contrivance and adjustable therewith, and means for affording relative adjustment lengthwise of the platen between said side guides without altering the position of said contrivance as a whole, said means operating to hold said side guides positively in set operative relationships.
65. 28. In a typewriting machine, the combination of a platen; a paper clamping contrivance adjustable lengthwise of said platen

- en; means for opening the clamping contrivance to receive paper, said means comprising a hand operated rock shaft, a crank arm slideable on said rock shaft; and a clip on said contrivance for effecting sliding movements of said crank arm.
29. In a typewriting machine, the combination of a platen; a pair of paper clamping contrivances adjustable towards and away from each other lengthwise of said platen, each contrivance comprising a pivoted clamping jaw; and means for opening the clamping jaws simultaneously in all positions of said contrivances, said means comprising a hand operated rock shaft, crank arms slideable on said rock shaft and connected to said clamping jaws; and clips on said contrivances for effecting sliding movements of said crank arms.
30. In a typewriting machine, the combination of a platen, a platen carriage, a bail pivotally supported from said platen carriage and comprising a cross bar, a plurality of paper clamps adjustably supported on said cross bar, said bail being movable on its pivots to carry said clamps into and out of working relationship with the platen, and stops for limiting the pivotal movements of said bail.
31. In a typewriting machine, the combination of a platen, a platen carriage, a bail pivotally hung from said platen carriage and comprising a cross bar normally disposed above the platen, a pair of paper clamp contrivances mounted on said cross bar and adjustable thereon lengthwise of the platen, each of said contrivances comprising a movable clamping or gripping member, and means for simultaneously moving the clamping members outwardly away from each other to completely open the clamps.
32. In a typewriting machine, the combination of a platen, a platen carriage, a bail pivotally hung from said platen carriage and comprising a cross bar normally disposed above the platen, a pair of paper clamp contrivances mounted on said cross bar and adjustable thereon lengthwise of the platen, each of said contrivances comprising a movable clamping or gripping member, means for simultaneously moving the clamping members outwardly away from each other to open the clamps, said means comprising a finger piece mounted on said bail, and automatically adjustable connections between said finger piece and each of said contrivances.
33. In a typewriting machine, the combination of a platen carriage, a platen thereon, a bail pivotally hung from said platen carriage, paper clamping contrivances supported by said bail, said bail being adapted to be swung on its pivots to carry said contrivances into and out of working position, and holding devices for preventing sidewise vibration of said bail when in working position.
34. In a typewriting machine, the combination of a platen carriage, a platen thereon, a bail pivotally hung from said platen carriage, a paper controlling contrivance supported on said bail, said bail being adapted to be swung on its pivots fore-and-aft of the machine to carry said contrivance into and out of working position, and holding devices for preventing sidewise vibration of said bail when in working position, said holding devices comprising a slotted part on said bail and a co-operating plate-like part on the support.
35. In a typewriting machine, the combination of a platen, a platen frame comprising a cross bar in front of the platen, a tally roll frame pivotally supported on said cross bar at the front and supported by the platen itself at the rear, said tally roll frame comprising upstanding arms, a tally roll device on said tally roll frame, a bail pivoted to said upstanding arms and normally disposed above the platen at its front side, and paper controlling contrivances supported on said bail for co-operation with paper received from the front of the platen, said bail being adapted to be swung upward and rearward to afford access to the tally roll devices.
36. In a front strike typewriting machine, the combination of a pair of clamping contrivances adjustably arranged above the printing face of the platen, each contrivance comprising a movable clamping jaw and a pair of side guides, the clamping jaws being adapted to hold a wide sheet and to maintain the side guides for a narrower sheet in working position, and means for moving the clamping jaws to release the wide sheet.
37. In a front strike typewriting machine, the combination of a pair of clamping contrivances adjustably arranged above the printing face of the platen, each contrivance comprising a movable clamping jaw and a pair of side guides, the clamping jaws being adapted to hold a wide sheet and to maintain the side guides for a narrower sheet in working position, means for facilitating adjustment of the sheets in a direction transverse of the platen, and means for swinging the clamping jaws outwardly to release the wide sheet so that it may be removed and replaced by another similar sheet, the movement of the clamping jaws exposing the guides for the wide sheet for use.
38. In a front strike typewriting machine, the combination of a platen, a carriage, releasable feed rollers co-operative with the platen at its under side, a release key for said feed rollers, a pair of paper controlling contrivances arranged above the printing face of the platen, each contrivance comprising a paper clamping jaw and two side

guides, one for a wide sheet and one for a narrower sheet, the clamping jaws being adapted to co-operate with the wide sheet, and means for simultaneously releasing the clamping jaws independently of said release key and for exposing the side guides for the wide sheet.

39. In a typewriting machine, the combination of a platen, a platen carriage, a supporting bar, a paper controlling contrivance, and means for adjustably securing said contrivance on said bar, said means comprising a projection on said contrivance, a wedge co-operative with said bar, and a screw for securing said wedge to said contrivance and wedging said bar between said projection and said wedge.

40. In a typewriting machine, the combination of a platen, a platen carriage, a supporting bar provided with oppositely beveled edges, a paper controlling contrivance provided with projections having inclined faces co-operating with one of the beveled

edges of said bar, a plate having a beveled edge co-operating with the other beveled edge of said bar, and means for securing said plate to said contrivance and clamping the bar at its beveled edges.

41. In a typewriting machine, the combination of a platen, a common adjustable support, two paper guiding contrivances on said support arranged to co-operate with two superposed work sheets at their same side edges, said work sheets being of different widths, and means for adjusting one of said guides relatively to the other so as to vary their distance apart lengthwise of the platen without disturbing their common support, said means being effective to hold said adjustable guide positively in set relationship with the associate guide.

Signed at the borough of Manhattan, city of New York, in the county of New York and State of New York this 16th day of January, A. D. 1924.

CLOYD E. BURNS.
